DESIGN FOR A LOUVERED LIGHT TRANSMITTING PANEL

Edward C. Zimmerman, Chicago, Ill., assignor to Patent License Corporation, Chicago, Ill., a corporation of Illinois

Application March 30, 1939, Serial No. 83,919

Term of patent 14 years

To all whom it may concern:

Be it known that I, Edward C. Zimmerman, a citizen of the United States, residing at Chicago, in the county of Cook and State of Illinois, have invented a new, original, and ornamental Design for a Louvered Light Transmitting Panel, of which the following is a specification, reference being had to the accompanying drawing, forming a part thereof.

In the drawing:

Fig. 1 is a perspective view of the louvered light transmitting panel, showing my new design;

Fig. 2 is a front view of the panel;

Fig. 3 is a side view of the same;

Fig. 4 is an end view of the same; and

Fig. 5 is a longitudinal section through the louvered light transmitting panel, taken on the line 5—5 of Fig. 2.

The dominant features of the design reside in the portions shown in solid lines.

I claim:

The ornamental design for a louvered light transmitting panel, substantially as shown and described.

EDWARD C. ZIMMERMAN
